Atty.

UNITED STATES PATENT OFFICE

ANDREW J. CHASE, OF BOSTON, MASSACHUSETTS.

BUTTER-DISH.

SPECIFICATION forming part of Letters Patent No. 295,111, dated March 11, 1884.

Application filed December 26, 1883. (No model.)

To all whom it may concern:

Be it known that I, ANDREW J. CHASE, a citizen of the United States, residing at Boston, in the county of Suffolk and State of Massachusetts, have invented new and useful Improvements in Butter-Dishes, of which the following is a specification.

In a prior patent, No. 275,587, granted me April 10, 1883, I have shown a refrigerating 10 butter-dish having a dome-cover for the dish or receptacle, with an ice-receptacle or refrigerating-chamber suspended therein from the top of the dome, the receptacle or chamber being of such smaller dimensions than the 15 interior of the dome as to form an air-circulating passage around the ice-receptacle or refrigerating-chamber. The construction shown in such patent as typical of the invention requires the removal of the suspended ice-receptacle from its inclosing-dome, in order to introduce ice or other refrigerant therein.

The object of my present invention, while following the principle of the invention set forth in that patent, is to furnish such a construction as will permit the introduction of the ice or other refrigerating agent into the receptacle without removal of the latter from the dome. To this end I construct the dome-cover with a neck at its top, the ice-receptacle or refrigerating-chamber being firmly united to such neck, from which point it is suspended within the dome. The neck upon the dome thus serves as a neck for an opening into the ice-receptacle, and it is provided with a suitable cover or lid. This construction is exemplified in the drawing, which is a sectional view of a dish embodying the invention.

A is the receptacle for butter or other articles, having a ledge or flange, a, designed to 40 receive and support the dome-cover B. This receptacle A may have a plain bottom, a'; or a' may be perforated and removable, serving merely as a support for the butter, and a bottom, h, provided, so as to form a space between a' and h for the reception of drip-water 45 of condensation, &c.

At the top of the dome-cover B a neck, b, is formed of any suitable size, to which is fitted a removable cover or lid, D, which may be 50 secured thereto in any desired manner—for instance, by mere friction, or by a screw-thread, or by a bayonet-joint. If desired, a

hoop, ring, or handle, E, may be attached to b, to facilitate its handling or removal from A. This dome B may be of any desired material— 55 silver or ordinary metals plated, or of glass or porcelain. If of the latter materials, the neck b would be of metal, secured thereto by cement or plaster in a manner well known in the arts. 60

An ice-receptacle or refrigerating-chamber, C, is provided, of such smaller dimensions than B as to form, when B and C are in proper relation, an air-circulating chamber, d, between them, as set out in the prior patent referred 65 to. This receptacle or chamber C is attached to the dome B and neck b at their point of union e in any suitable method, an opening, M, being left thereat in C, so that the neck b becomes practically common to both B and C. 70 This construction, as readily perceived, permits the introduction of ice or refrigerating agent into the interior of the ice-receptacle C without its detachment from the dome and from the exterior thereof upon the mere removal of the lid D from the neck b, which serves as a neck for both the dome and the receptacle. This is an important advantage, 75 simplifying the manipulations necessary to the use of the device, which as an entirety presents a pleasing, slight, and ornamental appearance, is exceedingly useful, and economically and certainly refrigerates or cools any article placed in the receptacle A.

Having thus described my invention, what I 85 claim is—

1. The combination, in a refrigerating butter or similar dish, of a dome or cover and an ice-receptacle suspended therein, the dome or cover and ice-receptacle being united together 90 at an opening common to both, whereby the ice-receptacle may be charged without detachment from the dome or cover, substantially as described.

2. The combination, in a refrigerating butter or similar dish, of a dome or cover, an ice-receptacle suspended therein, and a neck common to both, the dome and ice-receptacle being united at the base of the neck, whereby the ice-receptacle may be charged without detachment from the dome or cover, substantially 95 as described.

3. The combination, in a refrigerating butter or similar dish, of a receptacle for the ar-

article to be cooled, a dome or cover, an ice-receptacle suspended therein and rigidly attached thereto, and a neck or opening for the ice-receptacle, passing through the dome-cover and controlled from the exterior thereof, substantially as described.

4. The combination, in a refrigerating butter or similar dish, of a receptacle for the article to be cooled, a dome or cover, an ice-receptacle suspended therein and of such smaller dimensions than the interior of the dome or cover as to form an air-circulating chamber around the ice-receptacle, and a neck or opening common to both, the dome or cover and ice-receptacle being united together at the

base of the neck or opening, substantially as described.

5. The combination, in a refrigerating butter or similar dish, of a receptacle, A, a cover, B, a suspended ice-receptacle, C, a neck, b, common to both, and a cap or cover, D, substantially as described.

In testimony whereof I have hereunto set my hand in the presence of two subscribing witnesses.

ANDREW J. CHASE.
